US00D679788S

(12) **United States Design Patent**
Hoberg

(10) **Patent No.:** **US D679,788 S**
(45) **Date of Patent:** **** Apr. 9, 2013**

(54) **HEAT EXCHANGER**

(75) Inventor: **Svante Hoberg**, Åstorp (SE)

(73) Assignee: **Swep International AB**, Landskrona (SE)

(**) Term: **14 Years**

(21) Appl. No.: **29/335,025**

(22) Filed: **Apr. 7, 2009**

(30) **Foreign Application Priority Data**

Oct. 7, 2008 (EM) 001016141

(51) **LOC (9) Cl.** **23-03**

(52) **U.S. Cl.** **D23/323**

(58) **Field of Classification Search** ..... D23/317, D23/314, 332, 333, 334, 335, 337, 342, 351, D23/355, 378, 370, 381, 364, 336, 341, 323, D23/330; 416/244 R, 247 R, 53.1-53.3; 392/365, 367; D13/199, 179; 165/167

(57) **CLAIM**

The ornamental design for a heat exchanger, as shown and described.

DESCRIPTION

FIG. 1 is a perspective view of the bottom end plate of the heat exchanger; and,

FIG. 2 is a perspective view of the top end plate of the heat exchanger.

The views of the heat exchanger not shown do not form a part of the inventive design. The portions of the heat exchanger in phantom are presented as an environment, and do not form a part of the claimed design.

1 Claim, 2 Drawing Sheets

FIG. 1

FIG. 2
